(57) **CLAIM**

The ornamental design for an irrigation sprinkler weight, as shown and described.

DESCRIPTION

FIG. 1 is a top and side perspective view of my new irrigation sprinkler weight;

FIG. 2 is a side elevation, it being understood that the view from all sides is identical;

FIG. 3 is a top plan view;

FIG. 4 is a bottom plan view; and,

FIG. 5 is a sectional view taken along the line 5—5 of FIG. 3.
